(57) **CLAIM**

The ornamental design for a protective case for fishing sonar electronics, as shown and described.

DESCRIPTION

FIG. 1 is a front, left side perspective view of a protective case for fishing sonar electronics in an assembled configuration, showing my new design;

FIG. 2 is a front elevation view thereof;

FIG. 3 is a rear elevation view thereof;

FIG. 4 a left side view thereof;

FIG. 5 is a right side view thereof;

FIG. 6 is a top plan view thereof;

FIG. 7 is a bottom plan view thereof; and,

FIG. 8 is a perspective view of the protective case for fishing sonar electronics in an unassembled configuration.

1 Claim, 3 Drawing Sheets

FIG. 1**FIG. 2****FIG. 3**

FIG. 4**FIG. 5****FIG. 6****FIG. 7**

FIG. 8
